UNITED STATES PATENT OFFICE.

WILLIAM M. WHALEN, OF ERIE, PENNSYLVANIA.

SLAG-POCKET.

1,288,328.

Specification of Letters Patent. Patented Dec. 17, 1918.

Application filed June 4, 1918. Serial No. 238,145.

To all whom it may concern:

Be it known that I, WILLIAM M. WHALEN, a citizen of the United States, residing at Erie, in the county of Erie and State of Pennsylvania, have invented certain new and useful Improvements in Slag-Pockets; and I do hereby declare the following to be a full, clear, and exact description of the invention, such as will enable others skilled 10 in the art to which it appertains to make and use the same, reference being had to the accompanying drawings, and to the letters of reference marked thereon, forming part of this specification.

15 My invention relates to slag-pockets for open-hearth furnaces, and consists in providing such slag-pockets with removable slag receiving receptacles which are so placed in the slag-pockets that the sides and 20 bottom of said receptacles will be materially cooled, so that the slag will harden on the inner surfaces thereof. These and other features of my invention will appear herein-after, and are illustrated in the accompanying 25 drawings in which:

Figure 1, is a transverse vertical section of portions of an open-hearth furnace and slag-pocket, showing my invention installed therein.

30 Fig. 2, is a vertical section thereof on the line $\alpha-\alpha$ looking in the direction of the arrows in Fig. 1.

Fig. 3, is a horizontal section of the same on the line $y-y$ looking in the direction of 35 the arrows in Fig. 1.

In these drawings A indicates the melting tank of an open-hearth furnace which is enclosed in the usual setting walls A'. B, B indicate the side walls of the usual slag-pocket, which in my invention are provided 40 with under-cut recesses B'-B² at each side of the lower portion of the slag-pocket.

On the bottom of the slag-pocket I place longitudinal piers b, upon which I place 45 metal plates C, C having a space between the adjacent ends thereof as shown in Fig. 2. Upon these plates C, C I construct receptacles D of refractory brick or other suitable material, the side and end walls of 50 which extend upwardly from said plates C to a point slightly above the under-cut recesses B'-B², the side walls of said receptacle being provided with ribs d which engage the fixed walls at each side of the slag-pocket B to support the side walls of said

receptacle. These ribs d extend vertically along the intermediate portion of the side walls of the receptacles D so as to leave longitudinal air passages along the upper portion B' and lower portion B² of the 60 under-cut recesses.

There are also air passages between the piers b-b under the plates C C (see Fig. 1) which communicate with the spaces E and E' at the ends of the receptacles D. F, F, 65 indicate air ducts which lead from the upper longitudinal air passages B' B² to the stack (not shown) of the furnace, by means of which cold air is drawn into the passages B² B², and the passages between the piers b 70 under the receptacles, and caused to travel along the sides of the receptacles D between the ribs d for the purpose of cooling the walls of said receptacles.

The lower passages B² and the passages 75 between the piers b are open through the front wall G as shown in Fig. 2, so that cold air can enter freely, as indicated by the arrow in Fig. 2. In Fig. 2 I have shown by means of arrows in broken lines the travel 80 of cooling air in the under-cut recesses along the sides of the receptacles.

Under the receptacles D I place return-bend rods H, the arms of which are turned 85 upwardly so as to engage the inner ends of the receptacles D, so that a crane-tackle can be hooked thereto for the purpose of extracting the receptacles when it is desired to empty them. When the receptacles are removed they will ordinarily be broken up, 90 as the slag hardens on the walls thereof, and it is therefore necessary to replace them with new ones; but with my invention this can be done without much loss of time, as 95 the slag does not have to be cut off of the fixed walls of the pocket, and it is therefore not necessary to repair said fixed walls.

I am aware that others have devised removable slag receptacles, between which and the fixed walls they have placed filling material, but I am not aware of any construction of removable slag-pocket being provided with air cooling passages thereabout.

Therefore having shown and described 100 my invention so as to enable others to utilize the same, what I claim as new and desire to secure by Letters Patent is:

1. In a slag-pocket, fixed walls, spacing ribs extending inwardly therefrom, a removable slag receptacle having its outer sur- 110

face in contact with said spacing ribs, and means to cause air to circulate between said spacing ribs, substantially as set forth.

2. In a slag-pocket, fixed walls, a removable receptacle therein having the intermediate portions of its walls in spaced relation to said fixed walls, and means to draw cool air into the lower portion of the space around said removable receptacle, and heat-
10 ed air out of the upper portion of said space, substantially as set forth.

3. In a slag-pocket, fixed side and end walls having under-cut recesses in the lower portions of their inner surfaces, longitudinal
15 piers on the bottom of said pocket, a removable receptacle on said piers, the side and end walls of which extend upwardly slightly above said under-cut recesses, means to draw air out of the upper portions of said under-
20 cut recesses, and means to admit air under and at the side of said removable receptacles, substantially as set forth.

4. In a slag-pocket, fixed side and end walls, piers on the bottom of said pocket,
25 a removable receptacle therein supported on said piers, the upper edges of the walls of which contact with said fixed walls, and the intermediate portion of the side walls thereof being in spaced relation to said fixed

walls, vertical ribs on said receptacle side 30 walls to engage said fixed walls so as to support the side walls of said receptacles, means to draw air from the space between the walls of said receptacles and said fixed walls, and means to admit air thereinto, sub- 35 substantially as set forth.

5. In a slag-pocket, fixed side walls, piers on the bottom thereof, a metal plate supported on said piers, a slag receptacle on said plate, the upper edges of the side walls 40 of which engage said fixed side walls of the pocket, and the intermediate portion of the side walls of the receptacle being in spaced relation thereto, and means to cause a circulation of air along the walls of said receptacle, substantially as set forth.

6. In a slag-pocket, fixed walls, spacing ribs on the inner surface thereof, a removable slag receptacle in said slag-pocket the sides of which engage and are supported by said spacing ribs, spacing ribs supporting said slag-receptacle out of contact with the bottom of the slag-pocket, and means extending under said receptacle and engaging the rear thereof for removing it from the 55 slag-pocket, substantially as set forth.

In testimony whereof I affix my signature.
WILLIAM M. WHALEN.
